UNITED STATES PATENT OFFICE

CHARLES G. CURTIS, OF NEW YORK, AND EARLE R. NEWTON, OF JAMAICA, NEW YORK

TWO-CYCLE INTERNAL COMBUSTION ENGINE

Application filed October 1, 1931. Serial No. 566,244.

This invention relates to the scavenging and supercharging of two cycle internal combustion engine cylinders of the port-scavenged type. It applies particularly to 5 long stroke engines in which the path of the scavenging air through the cylinder is long.

The invention provides for a scavenging system comprising exhaust ports arranged 10 on one side of the cylinder near the end of the stroke remote from the combustion end, and air inlet ports arranged one above the other in two transverse planes, near the same end, and generally oppositely disposed to the exhaust ports. The air inlet ports are 15 characterized in that those in each transverse plane comprise oppositely disposed ports turned back toward the inlet side of the cylinder, like those described and claimed in applicants' earlier United States 20 Patents, Nos. 1,777,827 and 1,780,175.

The invention is applicable to both single acting and double acting two cycle engines, with or without inlet valves or exhaust valves.

25 The object of the invention is to improve the scavenging efficiency of two cycle engine cylinders which utilize inlet-ports arranged in two transverse planes. The features and advantage of the invention appear in the 30 description which follows and in the drawings. The invention, however, is not limited to the specific arrangements illustrated.

Figure 1 is a sectional elevation of an 35 engine to which the invention is applicable. The engine shown is a double acting engine with air inlet ports oppositely disposed to the exhaust port arranged in three transverse planes. The air inlet ports in the intermediate plane are arranged to serve each 40 end of the double acting cylinder alternately so that air-inlet ports in two planes are in use during the scavenging of each end of the cylinder.

45 Fig. 2 is a transverse, somewhat diagrammatic section through the air inlet ports in one transverse plane in accordance with the invention. In the illustrated embodiment the inlet ports in each transverse plane 50 are similar, that is, corresponding ports in

the two planes are alike, hence only one transverse section is shown.

Figs. 3, 4, 5 and 6 are diagrams showing longitudinal sections through the various ports in one plane and showing a changing 55 obliquity of the ports to the longitudinal axis of the cylinder in accordance with one embodiment of the invention.

Heretofore inlet-ports arranged in two planes have used either radial ports or ports 60 turned toward the exhaust port side of the cylinder and these arrangements do not give good scavenging efficiency although they do give a supercharge to the cylinder. By directing the ports in each plane back toward 65 the inlet side of the cylinder the same supercharge effect is obtained and the scavenging efficiency is very greatly improved.

In carrying out the invention we provide 70 a two stroke internal combustion engine comprising a cylinder 1, a reciprocating piston 2, exhaust ports 3, arranged in one side of the cylinder wall near the end of the stroke remote from the combustion end, and sets of air inlet ports 4 and 5 arranged in 75 two planes near the same end of the stroke in that part of the arc of circumference not occupied by the exhaust ports, that is, in that part of the cylinder wall generally opposite the exhaust ports.

In the drawings the sets of inlet ports 4 and 5 in each transverse plane are similar, that is, corresponding ports in the two planes are alike. They have the same angles, the same height, the same width and are in the 85 same longitudinal plane. However, the ports in the two planes may be dissimilar, that is, the ports in one plane may differ in size, angle or location from the ports in the other plane, provided each plane comprises 90 oppositely disposed ports turned back toward the inlet side of the cylinder. The ports in each plane are shown divided into two groups, four ports to each group. They are designated 4₁, 4₂, 4₃, 4₄, 4₅, 4₆, 4₇, 4₈, and 95 5₁, 5₂, 5₃, 5₄, 5₅, 5₆, 5₇, 5₈ and are arranged symmetrically about the center line 6 and turned back toward the inlet side of the cylinder. The air streams from the ports 4₁ to 4₄ inclusive oppose the streams from 100

the ports 4₅ to 4₈ inclusive. Similarly the two groups of ports in plane or set 5 oppose each other. The middle ports 4₁ and 4₅ are steeply oblique to the longitudinal axis of the cylinder and the end ports 4₄ and 4₈ are of lesser angle. The same is true of the ports in plane or set 5. This port arrangement prevents the incoming air from flowing transversely, or directly, across the cylinder to the exhaust ports and causes it to flow in a more or less longitudinal direction on the inlet port side of the cylinder to the cylinder cover and down the exhaust port side of the cylinder to the exhaust. 10

15 The operation of the two stroke cycle engine, having air inlet ports arranged in two transverse planes is well known and such engines are in common practice, and since the embodying of this invention in that engine does not in any way modify the cycle of operations it need not be described here.

20 What we claim as new and desire to secure by Letters Patent of the United States is:

1. A two-cycle internal combustion engine comprising a cylinder, exhaust ports and air inlet ports arranged in that end of the cylinder wall remote from the combustion end, the exhaust ports on one side and the air inlet ports on the other, said air inlet ports arranged in two transverse planes, the air inlet ports in each of the said planes comprising oppositely disposed ports turned back toward the inlet side of the cylinder wall so arranged that the air streams issuing from them come together as opposing streams and set up a flow toward the combustion end of the cylinder on the inlet side. 25

30 35

2. A double-acting two-cycle internal combustion engine comprising a cylinder, ex-

40

haust ports and air inlet ports arranged in the cylinder remote from the combustion end, exhaust ports on one side and the air inlet ports on the other, said air inlet ports arranged in three transverse planes, the air inlet ports in each of said planes comprising oppositely disposed ports turned back toward the inlet side of the cylinder wall, the ports in the middle plane serving both ends of the double-acting cylinder alter- 70 75

75 80 85

3. A two-cycle internal combustion engine comprising a cylinder, exhaust ports in one side of the cylinder wall and remote from the combustion end, air inlet ports arranged generally opposite the exhaust ports in two planes or sets, the ports in the middle portion of each set being oblique to the longitudinal axis of the cylinder, the ports in the end portions of each set being less steeply oblique and turned back toward the inlet side of the cylinder wall.

4. An engine according to claim 1 further characterized by the ports in the two planes being similar in that there are the same number of ports in each plane and corresponding ports in the two transverse planes are in the same longitudinal plane, have the same angles and are of the same size. 90

5. An engine according to claim 1 wherein the ports in the upper transverse plane reach higher up in the cylinder than the exhaust ports, and further comprising valve-means controlling said upper inlet-ports arranged to stay open after the exhaust ports are closed. 95 100
